UNITED STATES PATENT OFFICE.

JOHN A. ADLER, OF NORTH MILWAUKEE, WISCONSIN.

X-RAY-FILM HOLDER AND EXAMINING FRAME.

Application filed February 10, 1923. Serial No. 618,295.

To all whom it may concern:

Be it known that I, JOHN A. ADLER, a citizen of the United States, residing at North Milwaukee, in the county of Milwaukee and State of Wisconsin, have invented certain new and useful Improvements in X-Ray-Film Holders and Examining Frames, of which the following is a specification, reference being had to the accompanying drawings.

This invention relates to holders for supporting X-ray and other films for examination, and the general object of the invention is to provide a holder for this purpose which is particularly adapted for use in examining X-ray films or photographs, although not confined thereto.

A further object of the invention is to provide an electrically lighted film holder and examining frame which is simple, compact, efficient and practical, and in which the film will be held flattened out and free from any deformation and abundantly lighted so that the film may be carefully studied and all the details of the film made out.

A further object is to provide a film holder of this character with an illuminating bulb and with a parabolic reflector so constructed as to insure true parallel dispersion of the light rays so as to secure the highest possible amount of visual acuity.

Other objects have to do with the details of construction and arrangement of parts as will appear more fully hereinafter.

My invention is illustrated in the accompanying drawings, wherein:—

Figure 1 is a side elevation of a film holder constructed in accordance with my invention;

Figure 2 is a vertical sectional transverse view thereof;

Figure 3 is a section on the line 3—3 of Figure 2;

Figure 4 is an enlarged fragmentary vertical section;

Figure 5 is a fragmentary section on the line 5—5 of Figure 4;

Figure 6 is a top plan view of the reflector;

Figure 7 is a sectional view of the reflector on the line 7—7 of Figure 6.

Referring to these drawings, 1 designates a rectangular casing having vertical walls 2. These walls are preferably integral and may be of any desired height and proportions. This casing is preferably made of

sheet steel and the lower edge of the casing is secured to a cast frame 3 angular in cross section, which is preferably made of brass or steel. This frame 3 is formed with an upwardly extending flange 12 recessed at 13 for the reception of the wall 2, this wall 2 being held in place in this recess and against the flange 12 by means of the bolts 4.

The bottom 11 of the casing rests upon the flange 14 of the frame 3, as illustrated most clearly in Figure 4, and is also bolted to this flange 14 by means of the bolts 4. The vertical and horizontal flanges of the frame 3 are braced from each other at intervals by 70 the vertical webs 15, the bottom 11 being slotted to fit over these webs. The frame 3 at its corners is formed with feet 16 semi-spherical in shape but flat on the bottom and each foot being provided at its center with 75 a threaded aperture 17 for receiving a cap screw 18, which in turn secures a rubber pad 19 to the foot.

One of the walls 2 is provided with a switch 5 which is disposed in a convenient 80 place and is intended to make or break a circuit through the dry cell batteries 7 and an electric lamp or bulb 8. This bulb is disposed in the lamp socket 9 and these wires 6 pass from the battery 7, as shown in Figure 85 2, through apertures 10 in the lower plate 11 and thence upward through the base of the lamp and have suitable electrical connections to the electrodes of the lamp 8, as usual.

At the two upper corners of the casing an ear 20 is provided which projects above the upper edge of the casing and these ears receive a pintle 21 having its ends 22 reduced in diameter and adapted to receive the 95 threaded nuts 23 (see Figure 5). This pintle acts as a hinge for the cover frame 25. This cover frame is rectangular in plan and U-shaped in cross section so as to receive between the upper and lower flanges or webs of 100 this frame a sheet of clear plate glass 26. The sheet steel of the frame 25 is bent around the bar 21, as shown in Figure 4, thus securely holding the frame 25 to the casing 1 when the frame is being lifted in 105 order to insert a film for examination.

Opposite to the hinge for the supporting frame of glass 26 is a spring latch 27 which engages over the top of the frame 25 to hold the glass closed down upon the casing 1. 110 Immediately beneath the sheet of clear glass 26 there is disposed a sheet of glass 28 which

is frosted on its lower face in order that the image of the filament of the light bulb may not be seen. The glass 28 has its upper face beveled at its margins so as to provide a recess accommodating the lower flange of the steel frame 25, thus allowing the two sheets of glass 26 and 28 to be brought in very close proximity to each other and securely hold a film between the sheets for examination.

10 The sheet of glass 28 rests upon a strip of felt packing 30, which in turn rests upon the flanges 31 of a parabolic reflector 32 and acts as a cushion for the glass 28 and also prevents moisture or foreign substances, such as dust from entering the space below the glass.

15 The reflector 32 consists of a third dimension parabola, as shown most clearly in Figures 2 and 7, which is preferably made of one piece of sheet brass pressed to form a perfect parabola terminating across the corners of the casing, while the sides of the parabola from the line 33 extend directly upward parallel to the side walls of the casing 1, as at 32^a, and then terminate in the flanges 31, as heretofore described. The interior face of the reflector is silver plated and highly polished to thereby insure efficiency of illumination and to save current,

20 as this construction requires that only one bulb of relatively light wattage and high candle power be used, the reflector acting to greatly intensify this candle power. The lower wall of the reflector 32 is formed

25 with an opening 34 through which the lamp socket 9 extends. This lamp socket also extends through an opening 34^a in the bottom plate 11 and the lamp socket is formed with a shoulder bearing against the center of the reflector; and beyond this shoulder the lamp

30 socket is screw-threaded for the reception of a nut 36 in order to cause the lamp socket to hold the plate 12 and the reflector clamped securely together and thereby support the lamp socket rigidly in position.

It will be seen from Figure 4 that the edge of the flange 31 bears against the wall 2 of the casing 1 and that the edge of the packing 30 also bears against this wall, thus preventing the introduction of foreign matter into the space exterior to the reflector. The batteries 7 are of ordinary dry cell form and of sufficient capacity and are secured to the inside of casing 1 by means of straps 35 passing around the body of each battery and then bolted to the wall and bottom of the casing, as shown in Figure 3. Thus in order to replace the worn-out batteries it is only required to raise the cover 25, lift out the glass plate 28, remove the lamp socket 9, lift out the reflector 32 and replace the straps 35, and by reversing these steps the batteries may be readily replaced.

While I have illustrated dry batteries dis-

posed within the casing for causing the illumination of the lamp 8, I do not wish to be limited to this as any other source of power can be used to supply the required current. It is preferable, however, to use the batteries as thus the device may be removed to any desired place in a hospital or class room or to a place where no other power is obtainable, thus rendering the device particularly serviceable under all conditions.

While I have illustrated a construction which in its details I have found to be entirely satisfactory and which is believed to be a preferable embodiment of my invention, I do not wish to be limited thereto as it is obvious that many modifications of detail, proportion and arrangement of parts may be made without in any way departing from the principle of the invention as defined in the appended claims.

I claim:—

1. An X-ray film holder comprising a rectangular casing having a bottom and side walls, a parabolic reflector disposed within the casing at its corners extending up to the top of the frame and between the corners having vertical portions extending to the top of the frame, said reflector at its upper edge being formed with an outwardly extending flange bearing at its edge against the side walls, a strip of packing material resting upon said flange, a rectangular frame hinged to the side walls of the casing, a glass plate carried by said frame and a second glass plate resting at its margins upon said strip of packing material and so mounted as to permit the two glass plates to come in relatively close proximity to each other when the cover is lowered.

2. An X-ray film holder comprising a rectangular casing having a bottom and side walls, a parabolic reflector disposed within the casing at its corners extending up to the top of the frame and between the corners having vertical portions extending to the top of the frame, said reflector at its upper edge being formed with an outwardly extending flange bearing at its edge against the side walls, a strip of packing material resting upon said flange and at its side edge bearing against the side walls, a rectangular frame hinged to the side walls of the casing, the frame having upper and lower flanges, a glass plate disposed between said flanges, and a second glass plate resting at its margin upon said strip of packing material and having the upper face at its margin beveled to accommodate the lower flange of said frame whereby to permit the two glass plates to come in relatively close proximity to each other when the cover is lowered.

In testimony whereof I affix my signature.
JOHN A. ADLER.
